UNITED STATES PATENT OFFICE.

THOMAS F. ANDERSON, OF EAST LIVERPOOL, OHIO.

GRAVITY-KILN.

1,363,215.

Specification of Letters Patent. Patented Dec. 28, 1920.

Application filed May 26, 1920. Serial No. 384,426.

To all whom it may concern:

Be it known that I, THOMAS F. ANDERSON, a citizen of the United States, residing at East Liverpool, in the county of Columbiana and State of Ohio, have invented certain new and useful Improvements in Gravity-Kilns, of which the following is a specification.

The object of this invention is to provide an improved gravity kiln, particularly adapted for firing clay products and in fact any articles falling within the general field of ceramics.

A further object of the invention is to provide such an improved kiln with a construction particularly characterized by the fact that the longitudinal axis of the chamber within which the articles are fired extends in an upright direction, that is, at a substantial angle with the horizontal, even to the extent of being perpendicular if as desired, in order that when said chamber is charged the articles pass through said chamber under the direct influence of gravity, and without needing the aid of other means for propelling them.

This kiln may comprise either one or more substantially tubular ovens inclosing firing chambers of any suitable cross-section, and having the walls thereof constructed of fire-proof material such as fire-brick, and substantially at their midsection exposed to the influence of heat within a furnace, which it has been found especially advantageous to construct around the periphery of the said chamber or chambers at a point between the inlet and outlet ports.

With these general objects in view, the invention in practice comprises further details of construction hereinafter described in conjunction with the accompanying drawings, in which Figure 1 is a vertical longitudinal section of one embodiment of the invention; and Fig. 2 is a transverse section on the line 2—2 of Fig. 1.

Referring to the drawings, a kiln is illustrated which comprises a single tubular firing-chamber, surrounded at one point by a furnace which in turn is shown as having a pair of independent furnace sections with but one smokestack or outlet for the gases of combustion. Furthermore, these two sections may as herein shown comprise two grates from which the heated air currents pass toward each other before entering and rising through the stack.

The furnace can perhaps best be described as comprising a central section 1 of the foundation, having laterally extending wings 2, in which latter are positioned grates 3 upon which the usual fire is laid. These grates as shown in Fig. 2 may obviously extend throughout the length of the furnace from front to rear, or as shown in Fig. 1 the grate upon each side of the preferably tubular firing-chamber 4 may be subdivided into a forward section 3^a and a rearward section 3^b.

In either case the exposed ends of the grates are inclosed above their level by fire doors 5 and below their level by ash doors 6, operable independently of each other. Above the said grates brick arches 7 support the upper body portion of the furnace construction, while beneath said grates the furnace rests upon any suitable support 8 which in this instance is shown as comprising a floor, through which extends the lower end portion 9 of the firing-chamber 4, normally closed by any desired type of door 10, having suitable means represented by the weight 11 for maintaining the same in closed position, said door also being provided if desired with an aperture or grating as an inlet for air currents, which in passing upwardly through the chamber cause the articles to dry and then rise evenly and gradually in temperature throughout their respective masses before entering the zone of greatest heat.

Above the furnace may extend an upper floor 12 or suitable platform, above which extends the upper end portion 13 of the chamber 2, and through which portion the articles to be fired are fed into said chamber, after removing the cover 14. Said chamber is furthermore provided with a branch 15, which extends upwardly through the said upper floor and serves to create a flow of air through the firing-chamber and thus carry off the moisture from the articles being fired, as well as conveying an equal firing temperature to the entire lot of said articles throughout their mass.

The central portion of the tubular oven 105 firing chamber as hereinbefore stated passes through a heat zone and is surrounded by a flue 16, lined by firebrick 17 and from the sides of which the said oven is positioned in substantially uniform spaced relation by 110 means of midfeathers or ribs 18, formed of spaced firebrick or other non-inflammable

material. The heat of the furnace after starting from the fire-grates, passes around the oven, or firing chamber, as indicated by the arrows, and thence upwardly and 5 out through the smokestack 19 which latter also extends through and well above the upper floor or platform 12.

In charging a kiln of this construction, or in fact other constructions falling within 10 the scope of the present invention, the articles to be fired are loaded into the said chamber provided for the purpose until the latter is substantially or entirely filled. It will be apparent then, that some of the said 15 articles will fall to positions below the level of the furnace, until stopped by the door 10, or other form of closure provided for the purpose; or there may be first placed in the said chamber any suitable form of means 20 to temporarily restrain the said articles from falling below the zone of greatest heat until they have been thoroughly fired.

However, with the construction as shown, without such a means as last referred to, 25 after the articles within the heat zone are completely fired, those articles at the bottom of the chamber are removed in predetermined quantities at regular intervals until the fired articles reach the lower outlet, the unfired articles being replaced in 30 the chamber at the top, and the succeeding articles removed for shipment, or for further treatment as may be required by the type of articles being handled. Thereafter, 35 the raw articles are entered at the top and the same articles after being completely fired are taken with substantially continuous regularity from the lower outlet, thus entirely eliminating the common necessity of 40 charging a kiln, firing the same, and then permitting it to cool again before the charge can be removed and another charge inserted, and the kiln reheated to the required high temperature.

45 In describing this improved kiln, and illustrating the same by means of the drawings, reference has been made to obtaining the necessary heat to fire the porcelain articles by the burning of ordinary coal upon 50 one or more grates. However, while this is preferably proper, the invention contemplates as well the use of any suitable fuel whatsoever, as for instance natural gas, fuel oil, coal dust, and the like, and the slight 55 alteration of the mechanical construction necessary to make the substitution possible and efficient.

Having thus described my invention, what I claim and desire to protect by Letters Patent of the United States is:—

60 1. A kiln, comprising the combination of a tubular oven chamber, having an inlet and an outlet, said chamber extending in a slanting direction sufficient to cause solid articles 65 therein to progress by force of gravity only

toward said outlet, a source of heat, a heat-conveying channel surrounding a portion of said chamber between the ends thereof, and a flue extending upwardly directly from the said portion of said channel and removed 70 from the inlet to said chamber.

2. A kiln, comprising the combination of a substantially rectilinear tubular oven chamber, having openings in its opposite end portions, a source of heat, a heat conveying channel surrounding an intermediate portion of said chamber, and a flue to carry off the gases of combustion leading upwardly from the said intermediate portion of said channel and spaced from the 75 upper end of the latter.

3. A kiln, comprising the combination of a substantially rectilinear tubular oven chamber having a slant sufficient to cause bodies therein to progress only by force 85 of gravity toward the lower end thereof, a source of heat, a heat channel surrounding a portion of said chamber, and a flue leading from said channel directly upwardly and in spaced relation with the nearer end of 90 said chamber.

4. A kiln, comprising the combination of a substantially rectilinear tubular oven chamber having a slant sufficient to cause bodies therein to progress only by force of 95 gravity toward the lower end thereof, a heat channel surrounding the central portion of said chamber, a flue leading from the said central portion of said channel upwardly and in spaced relation with the nearer 100 end of said chamber, and a grate adapted to support a fire to supply heat to said channel.

5. A kiln, comprising the combination of a substantially rectilinear tubular oven 105 chamber having a slant sufficient to cause bodies therein to progress only by force of gravity toward the lower end thereof, a heat channel surrounding a portion only of 110 said chamber, a flue leading from said channel directly upwardly and in spaced relation with the nearer end of said chamber, and a plurality of sources of heat leading into said channel at spaced regions.

6. A kiln, comprising the combination of 115 a substantially rectilinear tubular oven chamber having a slant sufficient to cause bodies therein to progress only by force of gravity toward the lower end thereof, a heat channel surrounding a portion of said 120 chamber, a flue leading from said channel upwardly and in spaced relation with the nearer end of said chamber, and a plurality of grates adapted to support fire, and passageways arranged to conduct heat from 125 said grates into said channel at points angularly disposed about the periphery thereof.

7. A kiln, comprising the combination of a slanting tubular oven chamber of circular cross-section and having an inlet and an 130

outlet, a source of heat, and a flue operative to convey drafts from said heat source toward and around the central portion of said oven chamber in opposite directions, then 5 together above said chamber and directly upwardly from said chamber.

8. A kiln, comprising the combination of a slanting tubular oven of circular cross-section, a chamber also circular in cross-10 section through which said oven extends, a source of heat, and a flue operative to convey drafts from said heat source into said chamber and around the opposite sides of said oven, and means to carry off said drafts 15 from said chamber and leading upwardly therefrom.

9. A kiln, comprising the combination of a slanting tubular oven of circular cross-section, a chamber also circular in cross-section through which said oven extends, a 20 plurality of sources of heat, a flue from one source operative to convey drafts directly into a side of said chamber, a flue operative to convey drafts from another source into the lower portion of said chamber whence 25 the last-mentioned drafts encircle said oven in opposite directions, and means to convey all drafts from the upper portion of said chamber.

In testimony whereof I have affixed my 30 signature.

THOMAS F. ANDERSON.
